UNITED STATES PATENT OFFICE.

JOHN R. DOUGLASS, OF LOGANSPORT, INDIANA.

LOSS-PREVENTING DEVICE.

1,039,662.

Specification of Letters Patent. Patented Sept. 24, 1912.

Application filed April 23, 1910. Serial No. 557,181.

To all whom it may concern:

Be it known that I, JOHN R. DOUGLASS, a citizen of the United States of America, residing at Logansport, in the county of Cass 5 and State of Indiana, have invented new and useful Improvements in Loss-Preventing Devices, of which the following is a specification.

This invention relates to pockets, and has 10 for an object to provide a loss-preventing device therefor, the design being constructed particularly for use in the rule pocket of overalls and formed to provide spring gripping members for clamping engagement 15 with the rule upon insertion thereof in the pocket.

A still further object of the invention is to provide a loss-preventing device which is removably supported by or engaged with 20 the pocket when it is desired to wash the garment the device can be conveniently removed therefrom.

In the drawing, forming a portion of this specification and in which like numerals of 25 reference indicate similar parts in the several views:—Figure 1 is a front elevation of a portion of a pair of overalls showing my improved device applied to the pocket thereof. Fig. 2 is a detail vertical section 30 taken on the line 2—2 of Fig. 1. Fig. 3 is a detail perspective view of the spring gripping member.

The pocket A may be of any design but 35 preferably it is of a shape conforming substantially in configuration with the rule B. The front of the pocket is formed to provide a buttonhole C in which is removably fitted the button 1 on the jaw 2 of my improved 40 spring gripping member. The jaw 3 of the gripping member is connected with the jaw 2 by a curved stop-forming portion 4, the said stop-forming portion being located immediately above the bottom of the pocket for a purpose to be hereinafter described. 45 The spring gripping member may be constructed from a single piece of flat sheet metal and bent upon itself to form the herein described companion gripping jaws. Each jaw is provided at its upper end with 50 a horizontally disposed head 5 whose upper extremity or edge portion is curved outwardly, as shown. The outwardly curved portion of the head forms a relatively wide entrance space for the convenient insertion

of the rule. The heads are so constructed 55 that each forms a very broad clamping surface for engagement with the rule.

The construction of the device described is such that it can be conveniently applied to or removed from the garment, the latter 60 being extremely desirable when it is desired to laundry the garment. By arranging the gripping member so that the stop-forming portion 4 thereof is disposed immediately above the bottom of the pocket it 65 will be seen that when the rule is inserted in the pocket it will be engaged by the rule to prevent the thrust of the rule into the pocket from mutilating or injuring the bottom portion of the pocket. 70

While the article is designed particularly for use in connection with pockets designed for the reception of rules the article can of course be used as an effective loss-preventing device for numerous articles. 75

The button 1 is located directly adjacent the curved stop-forming portion 4 of the device. Very little movement of the jaws is made at this point and in view thereof the button when operatively associated in the 80 buttonhole of the garment will not tend to destroy the buttonhole nor will it tend to wear the same to an extent where the article would become accidentally disassembled from the pocket on frequent insertion of the 85 rule into the pocket.

I claim:—

A rule holder comprising a pocket having a button hole in its wall located near the lower end thereof, a U-shaped gripping 90 member having T-shaped terminals disposed within the pocket and the band of the U engaging the bottom portion thereof, and a button secured to one leg of the U-shaped member and extended through the button 95 hole of the pocket wall to hold said U-shaped member in a central position in the pocket, said U-shaped member being adapted to limit the downward movement of a rule inserted in the pocket and the T-shaped terminals being bent outwardly to normally 100 hold the pocket open to receive a rule.

In testimony whereof I affix my signature in presence of two witnesses.

JOHN R. DOUGLASS.
